UNITED STATES PATENT OFFICE.

EUGENE R. EDSON, OF CLEVELAND, OHIO.

CONDENSING APPARATUS.

SPECIFICATION forming part of Letters Patent No. 699,793, dated May 13, 1902.

Application filed January 13, 1902. Serial No. 90,102. (No model.)

To all whom it may concern:

Be it known that I, EUGENE R. EDSON, a citizen of the United States of America, residing at Cleveland, in the county of Cuyahoga and State of Ohio, have invented certain new and useful Improvements in Condensing Apparatus; and I hereby declare the following to be a full, clear, and exact description of the invention, such as will enable others skilled in the art to which it pertains to make and use the same.

This invention relates to improvements in condensing apparatus, and pertains more especially to condensing apparatus adapted for use in connection with a pump which is operated not only to facilitate a supply of gases and vapors to the condenser, but to force from the condenser any vapors or gases not condensed or liquefied within the condenser.

The primary object of this invention is to provide condensing apparatus which has a large capacity, which is efficient and reliable in its operation, and which is simple and durable in construction.

Another object is to maintain a liquid seal in the drain-pipe of the condenser, so that gases and vapors passing into but not condensed or liquefied in the condenser cannot escape through the said pipe.

With this object in view, and to the end of realizing other advantages hereinafter appearing, the invention consists in certain features of construction and combinations of parts hereinafter described, and pointed out in the claims.

In the accompanying drawings, Figure I is a side elevation, partly in section, illustrating condensing apparatus embodying my invention. Fig. II is a side elevation, largely in section, of the condenser proper. Fig. III is a top plan in section on line III III, Fig. II. Fig. IV is a transverse section of the water-distributing pipe-section of the condenser.

My improved condensing apparatus comprises a condenser proper or condenser, a well or reservoir arranged below and connected with the liquid-outlet of the condenser, and a pump or suction-creating device for facilitating the passage of gases and vapors into the condenser and for forcing from the condenser any gases and vapors not condensed or liquefied in the condenser.

Referring to the drawings, α represents the casing, which forms the primary water-receiving chamber 6 of the condenser proper or condenser. The casing α is provided at one side and near its lower end with a laterally and outwardly projecting pipe connection 20, to which the pipe 5, which is adapted and arranged to supply or conduct gases and vapors to the condenser, is attached in any approved manner. The pipe 5 forms, therefore, a passage-way extending to the lower portion of the chamber 6. The casing α is provided at its lower end and centrally of its bottom and below the discharging end of the pipe 5 with a downwardly-projecting pipe connection 21, to which a drain-pipe 8 is attached in any approved manner. The drain-pipe 8 is shown extending downwardly into a well or reservoir w , supplied with water or liquid, and has its lower end submerged in the body of liquid in the said reservoir. The casing α is provided at its upper end with an external annular flange 22, and an upwardly-bulging concavo-convex head 23, which extends over the upper end of the chamber 6, is removably secured to the said flange 22, preferably by bolts and nuts, as at 24. The casing α is provided at its upper end and at one side and preferably in close proximity to the flange 22 with a laterally and outwardly projecting pipe connection 25, to which the water-supply pipe 13 is attached in any approved manner.

A water-distributing cylindrical pipe-section 15 (see Figs. II and IV) is arranged horizontally within and transversely of the upper portion of the chamber 6, extending at its outer end through the pipe connection 25 and screw-threaded externally at the said end, and a union 26 connects the said section 15 with the water-supply pipe 13, which union is provided with an external flange 27, removably secured by bolts and nuts, as at 28, to a corresponding flange 29, formed upon and externally of the pipe connection 25. The pipe-section 15 is closed at its inner end, as at 16, and has the said end fitting into a corresponding annular flange 17, formed upon and internally of the casing α directly opposite the pipe connection 25. The pipe-section 15 is provided in each side thereof with two lateral apertures 18, which are made in

the form of slots extending longitudinally of the said section.

By the construction hereinbefore described it will be observed that the water supplied to the pipe-section 15 is discharged and distributed by the said section 15 laterally and transversely of the chamber 6 in sheets, and obviously any condensable gases and vapors passing at the pipe connection 20 upwardly into the chamber 6 come in direct contact with the water discharged from the section 15 and are thereby condensed or liquefied, and the resulting liquid will gravitate with the water to the bottom of the said chamber, where it escapes through the drain-pipe 8 into the well or reservoir *w*.

The head 23 of the casing *x* is provided upon the top thereof and centrally with a dome 30, containing a water-receiving chamber 31, and a sinuous upright tube 32 extends centrally through the said chamber 31 and in open relation at the lower end and centrally of the head 23 with the primary chamber 6 of the condenser, and a pipe *v* communicates with the upper end of the tube 32 and extends to and connects with the inlet of a suitably-operated pump *t*, which is employed in creating suction within the condenser. The water-supply pipe 13 has a valved branch 33 connecting with and discharging into the chamber 31. The valve 34 of the branch 33 is normally closed, but is, of course, opened preparatory to the operation of the condenser. The chamber 31 surrounds the tube 32, which has several lateral apertures 35 at suitable intervals longitudinally of the tube and arranged to discharge laterally into and transversely of the sinuous passage-way formed by the said tube. Preferably, as shown, an aperture 35 is formed in one side of the tube 32 and centrally between two apertures 35, formed in the opposite side of the tube, so that during the operation of the condenser a stream of water is discharged across the passage-way formed by the tube 32 in one direction and between two streams of water discharged across the said passage-way in the opposite direction.

The construction hereinbefore described and embodying the dome 30, the branch pipe 33, and the sinuous tube 32 and its apertures 35 is important and valuable, because thereby condensable gases and vapors escaping condensation in the primary chamber 6 of the condenser are effectually condensed or liquefied. The stream of water discharged from an aperture 35 in either side wall of the passage-way formed by the tube 32 strikes or impinges against and then gravitates adown the opposite side wall of the said passage-way, and water discharged into the said passage-way and any gases and vapors condensed or liquefied in the said passage-way gravitate to the chamber 6. The operation of the pump *t* is quite essential in order to pull or draw the gases and vapors upwardly in the condenser, and any gases and vapors

and accompanying air not condensed or liquefied within the condenser are conducted by the pipe *v* to the pump.

To prevent any interference with the sheets of water discharged from the pipe-section 15 in the primary chamber 6 of the condenser by water or liquid falling from the tube 32 and from the under surface of the head 23, a hood or umbrella-like device 36 is suspended within the upper end of the chamber 6 over the pipe-section 15 and a short distance from the inner surface of the head 23. The hood 36 is concavo-convex, with its convex side 80 uppermost, and conforms to and is almost as large in dimensions as the head 23. The hood is provided centrally with an aperture 37 for permitting the escape of gases and vapors not condensed within chamber 6 to the tube 32. The means for suspending the hood 36 from the head 23 comprises, preferably, bolts or screws or similar fastening devices, as at 38. It is obvious also that some of the gases and vapors not condensed or liquefied by the sheets of water discharged from the pipe-section 15 will pass between the hood 36 and the head 23 and there be condensed or liquefied by the water passing downwardly between the said parts 23 and 36 from the tube 32. It will be observed also that the pump *t* will during its operation draw or pull liquid from the body of liquid in the reservoir *w* more or less into the drain-pipe 8, according as the suction created by the operation of the said pump is increased or decreased, that a water seal is maintained in the said drain-pipe during the operation of the pump, and consequently gases and vapors not condensed or liquefied in the condenser cannot escape through the drain-pipe.

The well or reservoir *w* is preferably closed at its upper end by a cover 10, and the drain-pipe 8 is formed by two sections joined by a union 12 above the cover 10, with the lower section extending through the cover into the said reservoir, and obviously the said cover can be readily removed upon disconnecting the said lower pipe-section from the upper pipe-section of the drain-pipe by properly manipulating and thereby rendering the union 12 inoperative.

What I claim is—

1. Condensing apparatus comprising a water-receiving chamber; means for draining the said chamber of liquid received thereby or formed therein; means for conducting gases and vapors into the said chamber; a water-distributing pipe-section arranged within and transversely of the said chamber, which pipe-section is closed at its inner end and has slots formed in the sides and extending longitudinally thereof, and a water-supply pipe arranged to feed water to the said water-distributing pipe-section.

2. Condensing apparatus comprising a casing forming a primary chamber and having a head at its upper end over the said chamber; means for draining the said chamber of liq-

uid received thereby or formed therein; means for conducting gases and vapors into the said chamber; means for distributing water in the said chamber; a dome upon the aforesaid head; means for supplying water to the chamber of the dome, and a tube extending through the chamber of the dome and in open relation with the primary chamber of the condenser, which tube has lateral apertures arranged to discharge water from the chamber of the dome into the passage-way formed by the said tube.

3. Condensing apparatus comprising a casting forming a primary chamber and having a head at its upper end over the said chamber; means for draining the said chamber of liquid received thereby or formed therein; means for conducting gases and vapors into the said chamber; means for distributing water in the said chamber; a dome upon the aforesaid head; means for supplying water to the chamber of the dome and an upright tube extending through the chamber of the dome and in open relation, at its lower end, with the primary chamber of the condenser, and having lateral apertures arranged to discharge water from the chamber of the dome into the passage-way formed by the said tube.

4. Condensing apparatus comprising a casting forming a primary chamber and having a head at its upper end over the said chamber; means for draining the said chamber of liquid received thereby or formed therein; means for conducting gases and vapors into the said chamber; means for distributing water in the said chamber; a passage-way extending upwardly from and in open relation, at its lower end, with the said chamber; means for conducting water into the said passage-way, and a hood arranged in the upper end of the aforesaid chamber and above the aforesaid water-distributing means and having an aperture below the lower end of the aforesaid passage-way, substantially as and for the purpose set forth.

5. Condensing apparatus comprising a casting forming a primary chamber and having a head at its upper end over the said chamber; means for draining the said chamber of liquid received thereby or formed therein; means for conducting gases and vapors into the said chamber; means for distributing water in the said chamber; a dome upon the aforesaid head; means for supplying water to the chamber of the dome; an upright tube extending through the chamber of the dome and in open relation, at its lower end, with the primary

chamber of the condenser, and having lateral apertures arranged to discharge water from the chamber of the dome into the passage-way formed by the said tube, and a hood suspended in the upper end of the primary and lower chamber from the aforesaid head and above the aforesaid water-distributing means and having an aperture below the lower end of the aforesaid tube, substantially as and for the purpose set forth.

6. Condensing apparatus comprising a casting forming a primary chamber and having an upwardly-bulging concavo-convex head at its upper end over the said chamber; means for draining the said chamber of liquid received thereby or formed therein; means for conducting gases and vapors into the said chamber; means for distributing water in the said chamber; a dome upon the aforesaid head; means for supplying water to the chamber of the dome; an upright tube extending through the chamber of the dome and in open relation, at its lower end, with the primary chamber of the condenser, and having lateral apertures arranged to discharge water from the chamber of the dome into the passage-way formed by the said tube, and an upwardly-bulging concavo-convex hood arranged within the upper end of the primary chamber above the aforesaid water-distributing means and perforated below the lower end of the aforesaid tube, substantially as and for the purpose set forth.

7. Condensing apparatus comprising a casting forming a primary chamber and having a head at its upper end over the said chamber; means for draining the said chamber of liquid received thereby or formed therein; means for conducting gases and vapors into the said chamber; means for distributing water in the said chamber; a dome upon the aforesaid head; means for supplying water to the chamber of the dome, and a sinuous tube extending upwardly through the chamber of the dome and in open relation at its lower end with the primary chamber of the condenser, and having lateral apertures arranged to discharge water from the chamber of the dome into the passage-way formed by the said tube.

In testimony whereof I sign the foregoing specification, in the presence of two witnesses, this 8th day of January, 1902, at Cleveland, Ohio.

EUGENE R. EDSON.
